Cahill & Milans,

Inventor:

Charles B. Gilmore.
By W. A. Williams Attorney s.

UNITED STATES PATENT OFFICE.

CHARLES B. GILMORE, OF SPRINGFIELD, ILLINOIS, ASSIGNOR OF ONE-HALF TO JOHN F. WHITE, OF BLOOMINGTON, ILLINOIS.

BIT-STOCK.

No. 919,156.

Specification of Letters Patent. Patented April 20, 1909.

Application filed August 15, 1908. Serial No. 448,676.

To all whom it may concern:

Be it known that I, CHARLES B. GILMORE, citizen of the United States, residing at Springfield, in the county of Sangamon and 5 State of Illinois, have invented certain new and useful Improvements in Bit-Stocks, of which the following is a specification, reference being had therein to the accompanying drawing.

10 This invention relates to a bit stock and has especial reference to the driving mechanism therefor.

The invention includes a driver having a bit and means associated therewith for accelerating the speed of the bit and the driver carried thereby, and mechanism for releasing the operating connection of said first mentioned means, whereby the driver may be driven directly from the handle of the 20 instrument.

The invention also contemplates a tool of the character described which may be operated and adjusted by a single hand of the user.

25 More particularly the invention comprises a handle, a bit, a differential gear mechanism for the bit, an operative member for the latter, and a clutch member adapted to release the operative connection of the differential gear and couple the handle directly to the bit, with means for normally retaining said clutch in an inactive position.

The arrangement of parts and the novel details of construction will be pointed out in 35 the description hereinafter, reference being directed in this connection to the accompanying sheet of drawings forming a part hereof, and wherein a preferred embodiment of the invention is disclosed for the purpose 40 of illustration.

In the said drawings, Figure 1 is a longitudinal section, and Fig. 2 is a transverse section on the line $x-x$ of Fig. 1.

Referring now more particularly to the 45 drawing, in which like reference characters denote corresponding parts throughout the several views, 1 is a casing having an inwardly turned annular flange 2 at its inner terminal. Mounted to slide longitudinally 50 of the casing is a cap member 3, which is conveniently formed cup-shaped, with the

annular flange thereof loosely engaging the inner surface of the casing, and the body 3^a constituting the closing means for the outer end of the casing 1. A transverse partition 55 or abutment 4 is provided within the casing intermediate its ends and is apertured for the loose reception of the shank or bit 5^a of a screw driver or the like 5, it being within the contemplation of my invention to use tools 60 other than screw drivers. The bit 5^a projects without the inner end of the casing and terminates in an enlargement at its opposite end having a shoulder 5^b engaging over said partition. To the opposite side of the partition 65 a gear wheel 6 is keyed to the bit 5^a.

7 is a tubular sleeve rotatably mounted upon the bit 5^a and extending through the inner end of the casing, an enlargement 7^b of which constituting with the annular flange 70 2 a retaining wall for ball-bearings 8. An annular flange 9 is provided at the opposite end of the tubular member 7 and constitutes a support for rotatable gear wheels 10 arranged to mesh respectively with the gear 75 wheel 6 upon the bit 5^a, and an internal annular gear 11 upon the casing. The enlargement 7^b is preferably serrated or notched whereby the fingers of the operator may obtain a firm grip thereon and thereby rotate 80 the differential gears to impart to the bit and the part carried thereby a high speed.

From the description thus far it will be observed that the tool is double acting or reversible in that the screw driver may be 85 rotated in either direction at a high speed, and with but one hand of the user. In operation the palm of the hand is grasped about the handle 1 with the forefinger and thumb in engagement with the operating end 7^b of 90 the tubular member 7, movement being imparted to said tubular member through the medium of the forefinger and thumb with the result that the driver is actuated at an accelerated speed in either direction. 95

As before described the cap member 3 is slidably mounted within the casing 1. It has a pin and slot connection 12 with the casing which constitutes a guide for the cap and means for limiting its movement in 100 either direction. A spring 13 is inserted in the casing between the partition 4 and cap

3 and normally tends to hold the latter in its outward position. The cap 3 is also provided with a clutch face 14 arranged to engage when in innermost position a complementary clutch face 15 upon the end of the bit 5^a.

In the normal operation of the tool it will be noted that motion is imparted to the bit 5^a through the medium of the interposed differential gear. When, however, it is desired to release the gear connection and lock the parts together it is only necessary to push the cap member 3 inwardly against the action of the spring until the clutch face 15 thereof engages the complementary clutch face on the bit, when direct movement from the casing 1 to the bit 5^a may be had.

I claim:

1. In a tool of the character described a handle comprising a tubular casing having an internal annular gear intermediate its ends, a bit shank projecting at its lower end without the casing and otherwise inclosed by said casing, the bit shank having intermediate its ends gearing to coöperate with said first mentioned gear and a clutch member movably connected with the upper end of said casing and arranged to connect directly with said shank at a point above the gearing and within the casing.

2. In a tool of the character described, a handle comprising a tubular casing open at its respective ends, a bit shank projecting through the lower end of the casing and having a geared connection with the casing and means whereby the bit shank may have an independent connection with the casing comprising a clutch face upon the bit shank, and an auxiliary clutch member sleeved within the opening at the rear end of the casing and having a pin and slot connection with said casing.

3. A tool comprising a casing adapted to be grasped by the palm of the hand of the user, a bit, means for connecting the bit to the casing whereby the bit may be rotated by the casing, means whereby the casing may be released from said connection, a differential gear for the bit, the said gear being arranged within the casing and inclosed thereby, and an actuating device for the gear independent of the casing and constructed and arranged to be operated by the thumb and forefinger of the hand of the user.

4. A tool comprising a bit, a handle, means for coupling the bit to the handle for direct action, automatic means for releasing said coupling, and independent means for rotating the bit at an increased speed.

5. A tool comprising a bit shank, a handle, differential gearing within the handle for operating the shank, means extending without the handle and independent of the latter for operating the differential gearing to ro-

tate the shank at a high speed, and means for coupling the handle directly to the bit shank and locking the differential gearing comprising a clutch member slidably mounted within the handle, and constituting a closure for one end of the handle.

6. A tool comprising a bit shank, a gear upon the bit shank, a casing having an internal annular gear, a tubular member sleeved upon the bit shank and having a gear wheel arranged to mesh with the annular gear of the casing and the gear of the bit shank respectively, and said tubular member having an operating member extending without the casing.

7. A tool comprising a bit shank, a gear upon the bit shank, a casing having an internal annular gear, a tubular member sleeved upon the bit shank and having a gear wheel arranged to mesh with the annular gear of the casing and the gear of the bit shank respectively, said tubular member having an operating member extending without the casing, and means for locking each of said parts together and to the handle whereby the bit may be operated directly from the handle.

8. A tool of the character described comprising a bit shank having at its inner end an integral clutch member and a gear wheel intermediate its ends, a casing, gearing interposed between said gear wheel and casing, and a clutch member complementary to the clutch member of the bit shank carried by and movable relative to the casing.

9. A tool comprising a tubular casing constituting a handle having an opening at its opposite ends, a bit shank projecting through one of said openings, gearing interposed between the inner wall of the casing and shank, an operating member independent of the handle projecting without the casing for rotating the shank through said gearing, and a clutch member slidably connected with said casing for direct connection with the shank, the clutch having an operating part projecting through the other opening of the casing.

10. A tool comprising a tubular casing open at its respective ends, a bit shank fitting within one of said openings and projecting therewithout at one end, an integral clutch at the opposite end of the bit shank within the casing, a coöoperating clutch member between the casing and said shank clutch for operating the shank directly, the said coöoperating clutch having an operating part extending without the other opening of the casing, an interposed differential gear for operating the shank at a different speed, and means for operating the latter.

11. A tool comprising a tubular casing open at its lower end, a bit shank fitting within the casing and projecting therewithout at the lower end, an integral clutch at the opposite end of the bit shank within the

casing, a coöperating clutch member between the casing and said shank clutch for operating the shank directly, means for normally holding said clutch members separated, an interposed differential gear for operating the shank at a different speed, and means for operating the latter.

In testimony whereof I affix my signature in presence of two witnesses.

CHARLES B. GILMORE.
